THERMIONIC VALVE

James Bell, Pinner, England, assignor to The
M-O Valve Company Limited, London, England

Application June 1, 1949, Serial No. 96,429
In Great Britain May 24, 1948

2 Claims. (Cl. 315—39)

1

The present invention relates to a thermionic valve type oscillator for operation at high frequencies, for example, frequencies of the order of one thousand megacycles per second.

It is well known that thermionic valves for operation at high frequencies are provided in which a control grid electrode is mounted on a disc-seal, so that in the case of a triode valve, for example, the disc-seal is earthed in operation and thus provides substantial screening between the anode and the cathode, the anode and the cathode lying on opposite sides of the disc-seal.

When it is required to use such a disc-seal valve as an oscillator with the control grid electrode common to the two portions of the oscillatory circuit, however, it suffers from the disadvantage that the capacitance between the anode and the cathode inside the valve is usually too small to provide sufficient feed-back in the associated oscillatory circuit to sustain oscillations.

The object of this invention is to overcome the above disadvantage while retaining the advantages of low electrode-lead inductance obtained by the use of the disc-seal form of construction.

According to the present invention a high frequency oscillator is provided including a thermionic valve having at least an anode, a cathode and a control electrode all contained in an envelope, the anode being supported by a metal disc sealed through the walls of the envelope in such manner that the seals of the respective lead-in connections through the envelope to the cathode and control electrode lie on opposite sides of the disc, the oscillator having two high frequency resonant circuits associated therewith, the first of which is connected between the disc and lead-in connection to the cathode, and the second of which is connected between the disc and lead-in connection to the control electrode.

One arrangement according to the present invention will now be described, by way of example, with reference to the accompanying drawings, in which:

Figure 1 shows a diagrammatic central sectional view of a thermionic valve for use in an oscillator according to the invention; and

Figure 2 shows a coaxial-line circuit suitable for use with a thermionic valve such as is shown in Figure 1 parts of the outer conductors of the circuit being cut away to show internal details.

Referring to Figure 1, the valve is provided with a cylindrical glass envelope 1 through one end of which is sealed a hollow metal cylinder 2 which supports a hollow cylindrical nickel cathode 3, the envelope 1, cylinder 2, and cathode

3 all being coaxial. The cathode 3 is closed at the end furthest from the cylinder 2 and its outer longitudinal surface is provided with a suitable electron-emissive oxide coating. The cathode 3 is provided with a spiral heater 4, one end of which is connected to the cathode 3. The other end of the heater 4 is connected to a lead 5 which is disposed along the axis of the cylinder 2 and which is connected to a hollow metal pin 6 sealed into the outermost end of cylinder 2 by means of an insulating plug 7. The interior of the cylinder 2 is sealed by means of a glass plug 8.

The control electrode is in the form of a squirrel-cage grid 9 mounted so that it surrounds the cathode 3 coaxially. The grid 9 is supported by means of an annular copper disc 10 disposed perpendicularly to the longitudinal axis of the grid 9. The disc 10 is sealed through the envelope 1 in the conventional manner to provide the lead-in connection to the control electrode.

The anode consists of a hollow open-ended copper cylinder 11 disposed coaxially around the grid 9. The cylinder 11 forms an integral part of a second copper disc 12, which is disposed parallel to the disc 10 and is sealed through the envelope 1 in the conventional manner to provide the lead in connection to the anode. Attached to the disc 12 by means of tags 13 is a cylindrical metal shield 14 which is partially closed at the end further from the disc 12. The shield 14 serves to prevent deposition on the envelope 1 of any material evaporated from the cylinder 2 during operation of the valve.

The discs 10 and 12 are provided with flanges 15 and 16 respectively for the purpose of locating the valve accurately when it is plugged into an associated circuit.

Referring now to Figure 2, the circuit is made in two portions, an anode-cathode circuit having outer and inner conductors 17 and 18 respectively, and an anode-grid circuit having outer and inner conductors 19 and 20 respectively. The anode cathode and anode-grid circuits are respectively tuned by means of fingered pistons 21 and 22.

The end of the conductor 18 is enlarged into a hollow cylindrical cup 23 into which the outer end of cylinder 2 is designed to fit when the valve is plugged into the circuit. The metal pin 6 is adapted to connect with a heater lead (not shown) which runs along the interior of conductor 18, the heater lead and conductor 18 being insulated from each other. The conductor 17 has an internal diameter greater than the external diameter of the envelope 1, and is pro-

vided at one end with an external flange made in two parts, 24 and 25, separated by an annular mica sheet 26.

The end of conductor 20 is also hollow and is provided with fingers 27 which are adapted to contact the flange 15 of the grid disc 10 when the valve is plugged into the circuit. The conductor 19 is provided with an annular end plate made in two parts 28 and 29, separated by an annular mica sheet 30. The central hole 31 of part 29 is of such a diameter that when the valve is plugged into the circuit, the flange 16 of the anode disc 12 contacts the surface of the hole 31.

The part 25 is provided with four teeth 32, 33, 34, 35 which are adapted to slide under four arcuate plates 36, 37, 38, 39 attached to part 29 when the outer faces of parts 25 and 29 are brought into contact and the two portions of the circuit are rotated relative to one another about their longitudinal axes. The two portions of the circuit may thus be held together with the outer portion of the anode disc 12 clamped between the parts 25 and 29. The plate 37 is turned over at one corner to provide a stop.

It will be seen that when the circuit is assembled with a valve plugged in it, the anode disc 12 is electrically connected to the outer conductors 17 and 19 for alternating current, but not for direct current. Connection to the anode may be made by means of a tag 40 attached to the end plate of the grid-anode circuit.

It will be appreciated that a valve in an oscillator according to the present invention can be made with adequate capacitance between the cathode and control electrode to provide sufficient feed-back to sustain oscillation whilst at the same time making use of the disc-seal form of construction.

What I claim is:

1. A high frequency oscillator comprising a thermionic valve having a cathode, a control electrode and an anode all contained in an envelope, a metal disc sealed through the walls of the envelope and supporting the anode, a lead-in connection through the envelope to the cathode disposed on one side of the disc, and a lead-in connection through the envelope to the control electrode disposed on the opposite side of the disc, a first tunable coaxial line circuit having its outer conductor capacitively coupled to the disc and its inner conductor connected to the lead-in connection to the cathode, and a second tunable coaxial line circuit having its outer conductor capacitively coupled to the disc and its inner conductor connected to the lead-in connection to the control electrode.
- 15 2. A high frequency oscillator according to claim 1, in which the lead-in connection to the control electrode comprises a second metal disc sealed through the walls of the envelope and supporting the control electrode.
